UNITED STATES PATENT OFFICE.

JACOB ALDER, SR., OF ST. LOUIS, MISSOURI.

SEWER-OPENING APPARATUS.

1,241,894.

Specification of Letters Patent.

Patented Oct. 2, 1917.

Application filed December 20, 1916. Serial No. 138,070.

To all whom it may concern:

Be it known that I, JACOB ALDER, Sr., a citizen of the United States, and resident of St. Louis, in the State of Missouri, have

5 invented certain new and useful Improvements in Sewer-Opening Apparatus, of which the following is a specification containing a full, clear, and exact description, reference being had to the accompanying 10 drawings, forming a part hereof.

My invention relates to certain improved apparatus for use in opening up drains and sewers, and the invention consists in the novel mechanism, and method, hereinafter 15 fully described and particularly pointed out in the annexed claims.

The object of my invention is to provide an improved apparatus, whereby drains and sewers may be opened up with facility and 20 despatch, whenever they have been rendered inoperative by obstruction of whatever nature, without "digging" up and rebuilding the sewer; thus saving both time and expense.

25 In the drawings,

Figure 1 is a vertical section of a portion of a drain or sewer which has been rendered inoperative by an obstruction, and showing my improved "grabbing" device at work 30 therein.

Fig. 2 is a similar view, showing my improved articulated cutting tool, with a roller-cutter attached, cutting out grease which has obstructed the drain at a point beyond the 35 trap.

Fig. 3 is a similar view, showing my improved reticulated cutting tool in use as a "leader," in placing the cork-screw tool with its flexible wire-shaft in the drain a 40 distance beyond the trap thereof.

Fig. 4 is a vertical section, enlarged, of my improved telescopic dam and guide-pipe.

Fig. 5 is a vertical section, showing the practical application of the telescopic-dam 45 in use as a guide-pipe for the insertion of the cork-screw tool and its flexible-shaft through a hole (broken for the purpose) in a sewer or drain pipe.

Fig. 6 is a similar vertical section, show-

ing the earth-auger tool in use boring a 50 hole in the earth to afford access to the drain-pipe, before the insertion of the telescopic-dam and the flexible-shaft tool.

Fig. 7 is a detail of a portion of the telescopic-dam.

Fig. 8 is a detail plan of a portion of my 55 grab-tool.

Fig. 9 is a side-elevation of the grab-tool.

Fig. 10 is a detail end-elevation of the 60 grab-tool jaw.

Fig. 11 is a side-elevation of my improved articulated cutting-tool.

Fig. 12 is a plan of same.

Fig. 13 is a detail view of my auger-tool.

Fig. 14 is a detail view of my cork-screw 65 tool.

Fig. 15 is an end-elevation of same.

Fig. 16 is an end-elevation of the roller-cutter, and

Fig. 17 is a side-elevation of said roller- 70 cutter.

Heretofore, when a sewer, or a drain, has been stopped up by brick-bats, towels, leaves, grease, dirt, or any other obstructions, it has usually been thought necessary to go to 75 the trouble and expense of digging a wide and deep excavation in the earth, to uncover the obstructed sewer or drain, and to discover the location of the obstruction, and then tear up the sewer or drain in order to 80 get at and remove the obstructing article or thing.

By the use of my improved apparatus and method I do away with the expensive "digging" in every case, and effectively open the 85 sewer or drain at a comparatively small expense for time and labor.

The numeral 1 designates a common sewer or drain pipe, having the usual riser 2 and trap 3.

To remove the obstruction 4 (which may be a towel or dirty rags) from said trap it will only be necessary to insert through the said riser 2 the grab-tool, which consists of a shank 5 and a long pole 6 carrying the L-shaped jaws 7 and 8, and cause said jaws to grasp said obstruction, when same can be readily removed, and the pipe cleared.

Said jaws 7 and 8 have toothed or serrated edges 9 which bite into and securely hold said obstruction between them.

Said pole 6 is temporarily secured to said shank 5 by means of common bolts 10 which engage a series of holes 11 formed in said shank, so that said pole may be removed when desired, and used with other tools.

The said jaw 7 is fixed to said shank 5, preferably as shown, by making same integral with said shank, and forming a twisted portion 12 at the junction of said jaw and said shank, while the other jaw 8 is pivotally-attached to said shank by means of a common bolt 13.

A roller, or rope-sheave, 14 is mounted on a bolt 15 passed through apertures formed in said shank and in a brace 16, at a point near to said fixed-jaw 7, and a suitable rope or cable 17 passes down said riser 2 parallel with said handle or pole 6 and has its lower end passed over said sheave 14 and attached to the opposite (or movable) jaw 8, so that the latter may be closed in re-25 moving an obstruction, by merely pulling upon said rope.

The lower, or outer, end of said brace is secured to the said jaw 7 by means of a rivet 18, thereby firmly bracing said sheave-bolt 15. (See Fig. 8). A coiled spring 18^a normally holds said jaw 8 retracted.

After removing the obstruction from the said trap 3, if it is found necessary to go farther into the drain or sewer, to remove 35 caked grease, or any other similar obstruction, I make use of my articulated cutting-tool, whose shank 19 is secured to the pole 6 by means of bolts 10. (See Figs. 2 and 3.)

Said articulated cutting-tool is composed 40 of the shank 19, a short straight section 20, a short curved-section 21, and a suitable cutting-tool 22, all consecutively connected to said pole by means of common bolts or rivets, such as 10, all of which, except those 45 used in connecting said shank to said pole, act as pivots, to permit the different sections to move freely with relation to their pivots and to each other, except when limited by their fixed stop-brackets 23, which latter 50 will be described in detail hereinafter.

Said stop-brackets 23 are made with cross-bars which are extended across the sections, in the path of the next adjacent section, to engage the same and limit its pivotal-action, 55 and cause the section so limited to pass into and through a curved or angular passage-way, as in cleaning out the horizontal sewer or drains 1, shown in Figs. 2 and 3 of the drawings.

60 Said stop-brackets 23 are secured in place preferably by being welded to their sections.

Said straight section 20 and said cutting-tool, the latter designated on the drawing by the numeral 22, are preferably provided

with double parallel parts, and the cross-bars of said brackets 23 extend across the space between said parallel parts and have their ends welded or otherwise secured to each member of each pair of parts.

The cross-bars are also located on both 70 edges of said sections 20 and 22, the bars on one edge of same being narrower than those upon the opposite edges, for the purpose of permitting a greater movement of said sections upon their pivot-bolts 10 during opera-75 tion.

The free outer end of said cutter-section 22 is attenuated, to form a cutting-edge thereat, and the body near said cutting-edge is curved, preferably in the same direction as is the curved intermediate section 21, both of said sections being curved thus to facilitate their passage into the curved or angular portions of the drain or sewer, such curved construction permitting said 85 sections to fit the curve of such portions of the sewer and drain as the trap or "goose-neck" 3, and to slide thereon more efficiently than they could if such sections were 90 straight.

In Fig. 2 I have shown a roller-cutter attached, as an additional section, to the said cutting-tool 22, for the purpose of cutting out caked bodies of grease, as 24, which may have obstructed the drain or sewer, as I have 95 found that a roller-cutter is more efficient in such cases than a pointed cutter, like 22. Such pointed cutter merely "pokes" into, or scrapes off, the grease, while the roller-cutter has a roller 25 the periphery of which is 100 flattened, and is adapted to act as a "pusher," to force the grease forward, and thereby clear out the grease. Said roller 105 also acts to guide the cutting-tool 22 while same is being passed through the curved 110 traps and bends of a sewer or drain.

In Figs. 16 and 17 it will be seen that the outer end of the holder 26 for the said roller 25 is forked, and the roller is mounted in the space between the forks upon a suitable bolt or pintle 27, the body of said holder being curved in a direction opposite to that of the curve of said cutter 22.

The inner end of said roller-holder 26 is provided with a perforation 28 through 115 which passes a rivet or bolt 29, for pivotally securing said roller-cutter to said cutter 22.

In case it is desired to reach an obstruction which is located still farther up the sewer or drain 1, I make use of my cork-screw tool, which consists of a cork-screw-shaped cutter 29^a at the free end of a flexible-shaft 30, formed either integral therewith or separate therefrom, as desired.

The said flexible-shaft 30 may be 145 feet 120 long, if it is required to reach an obstruction which is that far away from the point of operation, as I have used the same in prac-125

tical work, and have successfully removed obstructions from a drain with a shaft of that length.

I preferably make said flexible-shaft of 5 a single length of steel wire of sufficient size, and form the cutter 29^a integral with the outer free end of said wire.

The operation of said flexible-shaft and its cutter 29^a is shown in Fig. 3, wherein the 10 said coiled cutter is first placed upon the said sharpened cutter 22, by inserting the free end of said last-named cutter within the coils of said coiled cutter, so that the latter will be firmly attached to and carried by 15 said cutter 22, so that the said coiled cutter will be forced into and along the passages of the drain or sewer, and the flexible-shaft 20 30 will follow after until the obstruction has been reached, when said sharpened cutter 22 is withdrawn from said coiled cutter, after which the latter is rotated (as is common cork-screw) to work its way into the obstruction and get a firm hold thereon. Any common tool may be used to rotate said 25 shaft.

After the coiled cutter 29^a has gotten a firm hold on the obstruction, the latter may be removed from the drain by withdrawal of the flexible-shaft carrying both cutter 30 35 and obstruction, or the cutter may be pushed farther up the drain and started toward its legitimate destination aided by the water in the drain, and thereby the drain may be opened.

35 Said articulated cutting-tool is only used as a "leader" for the said flexible-shaft tool in passing through the goose-neck or traps of the sewer or drain, farther passage of said coiled cutter 29^a along the drain, after the 40 trap has been passed through, being accomplished merely by pushing said flexible-shaft forward, and rotating it at the same time if desired.

The telescopic-dam, shown in Figs. 4 and 45 5, consists of a plurality of telescoping sections, of which I have shown in the present instance but two, an outer (or main) section 31 and an inner section 32.

Said main section has its upper end bent 50 at an angle, for the convenience of the workman, in inserting the tools hereinafter mentioned, and both sections are preferably made of sheet-metal and provided at each end with external bands 33, for stiffening 55 and protecting said ends from injury by contact with obstructions. The inner end of said section 31 also has an annular stop 34 which is contacted by the external band 33 on the outer end of said inner section 32, 60 to limit the telescopic movement of said sections in one direction, and an external band 35 fixed on said inner section at a point about midway of its length, by means of suitable rivets, as 36, or by means of

solder, or both rivets and solder, comes in 65 contact with the internal stop 34 of said outer section, to limit the movement of said sections in an opposite direction.

The uses to which my telescopic-dam and 70 guide-pipe may be put are many, as for instance, it is illustrated in Fig. 5 acting as an earth "dam", to prevent the earth from filling an aperture previously made in the earth by my auger-tool, presently to be described in detail, and which aperture is made 75 use of in passing other obstruction-removing tools, as my flexible-shaft 30 and cork-screw tool 29^a, into an opening 37 broken in the drain or sewer pipe 1, to reach the interior 80 of the latter, to reach and remove an obstruction therein.

A hole is first bored in the earth by means of the auger-tool 38, which consists of a common auger-bit having a long handle 39 pivotally attached to the shank of said bit 85 by means of a bolt 40 passed through the overlapping adjacent parts of said handle and shank, said hole being bored at an angle for convenience of the workman, as shown in Fig. 6, until the drain or sewer is reached; 90 then said telescopic-dam is inserted in said hole; then the opening 37 is made in said drain or sewer by forcibly striking said drain with the end of the said telescopic-dam, or with the end of the said auger-bit, 95 or any other heavy tool, such as a common crow-bar; and finally the flexible-shaft carrying the cork-screw cutter 29^a is inserted 100 into said dam and passed therethrough into said drain or sewer through said opening 105 37, and the obstruction removed.

Or, if preferred, the articulated-tool, having the sharpened cutter 22 at its free end, may be passed into the drain or sewer in the manner just described, to remove an 105 obstruction.

A common set-screw 41 is threaded through the external band 33 and the internal stop 34, at the inner end of said main section 31, so that the inner end of said set-screw will engage the desired one of the external bands 35 on said inner section 32, whereby the telescopic-dam may be adjusted to the required length.

In view of the above description, no further directions as to the operation of my invention need be given.

I claim as my invention the following:

1. A cork-screw tool, for use in cleaning 120 out sewers and drains, and consisting of a long flexible-shaft having a cork-screw-shaped cutter at one of its ends, a long pole, and an articulated tool composed of pivoted sections which are adapted to engage and pass through traps and bends in the sewer or drain, and to engage within and carry said cork-screw-shaped cutter into and through such traps and bends, so that said 125

cutter may reach and engage obstructions which are located beyond the traps and bends out of reach of the articulated tool alone.

5 2. Sewer cleaning apparatus comprising a telescopic dam, in combination with a long flexible shaft having a cutting tool at one end, said dam adapted to prevent the earth from caving upon said long flexible shaft

while the tool is being used in a buried 10 sewer or drain.

In testimony whereof, I have signed my name to this specification, in presence of two subscribing witnesses.

JACOB ALDER, SR.

Witnesses:

HENRY L. HIGDON,
JOHN C. HIGDON.
